UNITED STATES PATENT OFFICE.

LOUIS STOCKER, OF KNOXVILLE, TENNESSEE, ASSIGNOR OF ONE-HALF
TO ERNEST KOELLA, OF ROCKFORD, TENNESSEE.

DESIGN FOR A MANTEL-SHELF.

No. 37,567.

Specification for Design.

Patented Sept. 26, 1905.

Application filed June 26, 1905. Serial No. 267,146. Term of patent 14 years.

To all whom it may concern:

Be it known that I, LOUIS STOCKER, a citizen of the United States, residing at Knoxville, in the county of Knox and State of Tennessee, have invented a new, original, and ornamental Design for Mantel-Shelves, of which the following is a specification, reference being had to the accompanying drawing, forming part thereof.

The figure is a perspective view of a mantel-shelf showing my new design.

I claim—

The ornamental design for a mantel-shelf, as shown.

LOUIS STOCKER.
